UNITED STATES PATENT OFFICE.

WILLIAM T. THACKER AND CHRISTOPHER C. GOSNELL, OF GREENVILLE, SOUTH CAROLINA.

ADJUSTABLE WARP-STOP-MOTION DROP-WIRE RACK FOR LOOMS.

1,226,409.

Specification of Letters Patent. Patented May 15, 1917.

Application filed April 7, 1916. Serial No. 89,703.

To all whom it may concern:

Be it known that we, WILLIAM T. THACKER and CHRISTOPHER C. GOSNELL, citizens of the United States, residing at Greenville, in the county of Greenville and State of South Carolina, have invented certain new and useful Improvements in Adjustable Warp-Stop-Motion Drop-Wire Racks for Looms; and we do hereby declare the following to be a full, clear, and exact description of the invention, such as will enable others skilled in the art to which it appertains to make and use the same.

The invention relates to an adjustable warp stop motion drop wire rack for looms.

The object of the present invention is to provide a simple, practical and comparatively inexpensive adjustable warp stop motion drop wire rack for looms equipped with a center support and adapted to be readily lifted from a loom with the pattern to be retied, and capable of effectually preventing the drop wires or devices from becoming tangled and of enabling the same to be easily and quickly tied.

A further object of the invention is to provide a drop wire rack of this character adapted to materially lessen the expense of operating looms and capable of increasing the output of the same and adapted also to not only save patterns for warp tying machines but to also be used to great advantage in drawing new styles or patterns of goods.

It is also an object of the invention to provide a warp stop motion drop wire rack with which it will be impossible for the yarn to come in contact with the bottoms of the drop wires or drop devices and thereby prevent such devices from becoming misplaced or tangled.

With these and other objects in view, the invention consists in the construction and novel combination of parts hereinafter fully described, illustrated in the accompanying drawings, and pointed out in the claims hereto appended; it being understood that various changes in the form, proportion, size and minor details of construction, within the scope of the claims, may be resorted to without departing from the spirit or sacrificing any of the advantages of the invention.

In the drawings:

Figure 1 is an elevation of an adjustable warp stop motion drop wire rack and center

support, constructed in accordance with this invention.

Fig. 2 is a similar view the rack being removed from the center support and the drop wires or devices being supported in an elevated position by upper rods.

Fig. 3 is a vertical transverse sectional view on the line 3—3 of Fig. 1.

Fig. 4 is a similar view on the line 4—4 of Fig. 2.

Fig. 5 is a transverse sectional view on the line 5—5 of Fig. 2.

Fig. 6 is a detail perspective of the central support.

Like numerals of reference designate corresponding parts in the several figures of the drawings.

In the accompanying drawings in which is illustrated the preferred embodiment of the invention, the adjustable warp stop motion drop wire rack comprises in its construction vertical end plates 2 and lower horizontal connecting bars and a pair of lower horizontal rods 4. The lower longitudinally disposed connecting members or bars 3 consist of flat bars having their side faces arranged in vertical planes and in parallelism and secured in openings 5 and recesses 6 of the end plates by transverse fastening devices 7. The lower bars 3 over which the yarn passes are located at a point intermediate of the upper and lower ends of the end plates and the openings 5 which receive the center longitudinal bar are located midway between the side edges of the said end plates. The end plates which are permanently secured to the ends of the longitudinal bars 3 are provided above the same with perforations 8 arranged in pairs and located at different elevations and adapted to receive upper and lower longitudinal rods, the lower rod 4 extending through the upper slot 10 of the drop wires or drop devices 11 and the upper rod 12 being adapted to be passed through the upper slot for supporting the drop wires in an elevated position when the rack is to be removed from a loom for enabling the drop wire devices to be tied in position for preserving the pattern and for enabling the drop wire devices and the rack to be replaced in the loom when it is desired to use the pattern again. By this construction the drop wires or drop devices are prevented from becoming misplaced or entangled and a material saving in the ex-

pense of operating looms is effected and the output is increased. The end plates are provided at the side edges with set screws or clamping screws 13 for detachably engaging the ends of the upper and lower rods for securing the same in position. The end plates are shown equipped with supplemental plates 14 riveted or otherwise secured to the inner faces of the end plates and extended above the same and provided with perforations 15 for the reception of horizontal rods in the adjustment of the same but instead of providing supplemental plates the length of the end plates may be readily increased to secure the desired range of adjustment as will be readily understood.

When the rack is in position in a loom, it is supported in the center by a central support 16 designed to be permanently mounted upon the loom frame consisting of a standard or stem 17 provided at its upper end with a horizontally disposed arm 18 and supporting a lower horizontally extending arm 19 arranged in parallelism with the upper arm 18. The support 16 may be fastened to the loom frame by any suitable fastening devices and the drop wire rack may be detachably supported upon the loom frame in any desired manner.

30 The upper arm 18 is provided in its upper edges with notches or recesses 20 to receive the lower rod of the rack and the lower arm which has an attaching portion or flange 21, is provided in its upper edge with rectangular recesses 22 located at the central and terminal portions of the arm 19 and arranged to receive the lower longitudinal bars. The flange 21 is riveted or otherwise secured to the stem or standard of the central support 35 and the said stem or standard is provided at its lower portion with a perforation 23 for the reception of a suitable fastening device for mounting it in position on a loom.

The warp threads not shown pass through 40 the lower slot and support the drop wires or drop devices in an elevated position and these drop wires or drop devices which constitute detectors are adapted to fall when one of the warp threads break and arrest 45 the reciprocation of the members with which they coact and thereby effect a stopping of the loom in the usual manner. The drop wires or drop devices extend downwardly between the intermediate and side longitudinal bars 5 and 6 which support the yarn so 55 that there is no liability of the yarn coming in contact with the lower end of the drop wires or drop devices and displacing the same.

60 The yarn passes over the lower longitudinal bars and under the lower rod and when it is desired to remove the rack from the loom the upper rods are placed in position through the upper slots of the drop wires or drop devices which are thereby support-

ed in such elevated position that they occupy when in use or operation and they may be easily and conveniently tied in such position so that the design or pattern can be preserved for instant reuse. This will greatly lessen the cost of tying up patterns and will enable the same to be arranged for use in a loom with much less time than has heretofore been possible thereby saving both the expense of handling such devices and also increasing the output of the loom. In fact in a mill of five thousand two hundred and sixty-four spindles and twelve hundred and eighty-eight looms it has effected a saving of \$10.00 a day in actual labor and has increased the production 5%. The tangling of the drop wires or drop devices has resulted in more trouble than anything else encountered in the operation of a loom and the elimination of this trouble will greatly facilitate the operation of looms. Furthermore, the rack not only contributes to the preserving of the pattern in use on a loom but greatly facilitates the making of new patterns owing to the supporting of the drop wires or drop devices by the top rod. Also the central support of the rack permits the latter to be easily lifted off of it in removing the rack from a loom.

What is claimed is:—

1. A warp stop motion drop wire rack adapted to be placed on and removed from a loom bodily and including fixed lower rods adapted to pass through the upper slot of the drop wires and supporting means carried by the rack and coöperating with the fixed rods to hold the drop wires against vertical movement for holding the drop wires in an elevated position and for enabling the pattern to be tied with the drop wires in such position.

2. A warp stop motion drop wire rack including upper and lower longitudinal rods adapted to pass through the upper slot of the drop wires arranged to hold the latter against vertical movement, the lower rods being fixed, the upper rods being removable and supporting the drop wires in an elevated position when the rack is removed from a loom.

3. A warp stop motion drop wire rack for looms including spaced end plates, center and side longitudinal bars connecting the end plates and spaced apart to receive the lower portions of the drop wires and adapted to support the yarn to prevent the same from coming in contact with the lower ends of the drop wires, and rods carried by the end plates and arranged to extend through the upper slots of the drop wires and hold the latter against vertical movement.

4. A warp stop motion drop wire rack for looms including spaced end plates, center and side longitudinal bars connecting the end plates and spaced apart to receive the

lower portions of the drop wires and adapted to support the yarn to prevent the same from coming in contact with the lower ends of the drop wires, and upper and lower rods supported by the end plates and adapted to pass through the upper slots of the drop wires and arranged to hold the latter against vertical movement, the upper rods being removable and serving to support the drop wires in an elevated position when the rack is not in use.

5. An adjustable warp stop motion drop wire rack for looms including vertical end plates, lower central and side bars connect-

ing the end plates, the latter being provided above the said bars with perforations and upper and lower longitudinal rods arranged in the said perforations and adjustable on the end plates, said rods being arranged to hold the drop wires against vertical move- 15
ment. 20
